UNITED STATES PATENT OFFICE.

CECIL M. CLARKE, OF CHICAGO, ILLINOIS.

INSULATING MATERIAL.

1,128,759.

Specification of Letters Patent. Patented Feb. 16, 1915.

Application filed January 11, 1913. Serial No. 741,378.

To all whom it may concern:

Be it known that I, CECIL M. CLARKE, a citizen of the United States, residing at Chicago, in the county of Cook and State of Illinois, have invented a new and useful Improvement in Insulating Material, of which the following is a specification.

My invention relates to an improvement in the class of insulating material for pipe and boiler covering, walls and the like; and it relates particularly to an improvement in the construction of non-conducting covering in the class referred to, comprising a plurality of plies, more especially of asbestos sheets, each ply or layer being composed of a flat or relatively-smooth sheet of the material and a corrugated sheet thereof cemented to one of its faces to produce dead-air spaces.

The particular construction of non-conducting material thus outlined is in extensive use, and is regularly manufactured in long sheets which are cut up into suitable lengths imposed one upon the other to produce a desired thickness for application to the insulating purpose, being rolled into tubular form for use on pipes, or provided in block or other form for different other applications.

The primary object of my invention is to greatly increase the number of air-spaces in the material and also render them relatively small and thus more confining to the air they contain, with the obvious advantage of enhancing the insulating property of the material, and at the same time to compact the structure with the advantage of providing a relatively-large number of the layers and air-spaces without increasing the thickness of the material, to thus further enhance the insulating property of the latter.

In the accompanying drawing, Figure 1 is an edge-view in section and in somewhat exaggerated proportions, of a portion of a layer of the aforesaid known insulating material, formed of a flat sheet of asbestos and a corrugated sheet of the same cemented thereto; Fig. 2 is a similar view of the same, showing the corrugations folded upon themselves to produce my invention; Fig. 3 shows a plurality of the layers of Fig. 2 imposed one upon the other to produce my improved insulating material in suitable thickness, and Fig. 4 shows, by a view in end elevation, the material of Fig. 3 reduced to

tubular-roll form, for pipe-covering but with the flat sheets and the corrugated sheets having the corrugations flattened down or folded, extending only partway about the tube-formation to simplify the illustration.

A flat sheet 5, preferably of asbestos, has cemented to one surface thereof a regularly-corrugated sheet 6, also preferably of asbestos, to form between the two sheets dead-air spaces 7, the two sheets constituting a layer, which is produced by suitable machinery in a usual way. I mash down the corrugations, preferably by passing the layer between suitable rollers (not shown), thereby to fold them upon themselves all in the same direction into the condition clearly illustrated in Fig. 2, which is the preferred condition, though they may be otherwise mashed down, and not necessarily all in the same direction, without departure from my invention.

With the structure of Fig. 2 in a pile of layers, as represented in exaggerated form in Fig. 3, to provide my improved article in suitable thickness for its purpose, the spaces 7 are still present but are reduced in size, and between the folded end 8 of each corrugation and the flat sheet 5 of the next layer another air-space 9 is formed, thus doubling the number of air-spaces in the structure and materially reducing them in size, by the flattening and folding of the corrugations, to more thoroughly distribute and confine the air-content throughout the structure and at the same time so compact the latter as to enable a relatively-large number of the layers to be used for a given thickness of the material, thus augmenting its insulating effect. As will be seen, the described construction produces two series of the air-spaces between each pair of the sheets 5, the members of the series being in staggered relation to each other.

When the structure of Fig. 3 is formed into a tube, according to Fig. 4, for a pipe-covering, to enable it to be spread for the application, it is split, as shown at 10, where flaps 11, 11' overlap each other of a fabric jacket 12 cemented about the tube as a finish therefor; and after adjusting the covering on a pipe and bringing the spread ends together, the flaps are cemented in their overlapping relation.

What I claim as new and desire to secure by Letters Patent is:—

As a new article of manufacture, non-conducting material comprising a plurality of layers each formed of a sheet of insulating material and a corrugated sheet of the same secured to a surface thereof and having the corrugations folded upon themselves in the same direction to form a plurality of series of air-spaces between the successive first-named sheets.

CECIL M. CLARKE.

In presence of—

D. C. THORSEN,
A. C. FISCHER.
